UNITED STATES PATENT OFFICE.

NINIAN A. BLACKHAM, OF LONG BRANCH, AND GODFREY N. ROBILLARD, OF TORONTO, ONTARIO, CANADA; SAID BLACKHAM ASSIGNOR TO SAID ROBILLARD.

ELEVATOR.

Application filed June 7, 1922. Serial No. 566,596.

The principal objects of this invention are to provide means for facilitating the handling of motor cars for storage in buildings which will be safe and reliable and will 5 effect a considerable saving in time in receiving and releasing the cars from storage.

A further object is to provide a storage means which may be installed in a very compact and restricted space.

10 The principal feature of the invention consists in the novel arrangement of a plurality of pivotal carriers upon a structure rotatably supported upon roller supports and in the arrangement of landing stages 15 at various elevations to enable the movement of the cars to or from the pivotally supported carriers.

In the drawings Figure 1 is a side elevational view of a structure constructed in 20 accordance with this invention.

Figure 2 is a front elevational view of a multiple unit.

In the handling of motor cars in urban centres it is almost impossible to provide 25 a quick service for receiving and discharging cars without the use of a very considerable floor space arranged in one area and the use of elevators of the ordinary kind is extremely slow.

30 This invention contemplates the adaptation of a rotary type of elevator for this service which of course can be adapted for other uses. According to this invention a rotatable member 1 in the form of a large 35 double wheel comprising the members 2 and 3 which are connected together by transverse shafts 4 arranged adjacent to the outer circumference and upon these shafts are pivotally hung the carriers 5 which are sufficiently large to accommodate a motor car. 40 The members 2 and 3 are carried on roller supports 6 arranged in the base structures 7 which may be of steel or concrete or timber construction, sufficient to support the weight of the fully loaded carriers.

The wheel is free to rotate upon the roller supports and the building in which the wheel is housed is provided with landing stages 45 A, B, C and D at different levels so that several cars may be discharged from the rotatable member at once.

It may be necessary to provide hinged gang-ways 8 such as shown at the landing D in order to bridge the gap between the

carrier and the landing necessary to allow 55 the carriers to move in their orbit.

The member 1 may be rotated in various manners but is here shown operated by means of a large spur gear wheel 9, driven by a pinion 10. The spur wheel is connected to a central axle which is connected to the members 2 and 3. The members 2 and 3 may be duplicated to provide a considerable number of carriers as shown in Figure 2 and such a device may be utilized 65 in its entirety as a storage member without other accommodation.

When a plurality of these rotatable members is provided it is of course necessary that each individual wheel be supported from 70 the bottom. This construction is preferable to the weight being carried by a central shaft which would have to be of enormous proportions, whereas the base supporting structure may be of very simple design.

75 In the use of this device, cars may be driven in on the ground floor level B and on to the carrier and immediately upon being secured, the member 1 may be rotated to bring the next carrier into line, the movement being up one side and down on the other. If a supplementary storage space is available on the basement level A a car may be driven off the carrier, thus leaving it 80 available for entrance from the opposite side 85 when it rises again to the ground level. The whole structure may be utilized for delivering cars to the various levels A, C and D.

A device such as described will enable cars to be taken on to the wheel very rapidly 90 and immediately they are loaded on to the elevator a slight movement will bring another to the available position for loading and while this is being loaded others that have been loaded may be emptied if desired. 95 By this means a very rapid service can be obtained which is a very desirable feature.

The driving means is herein shown as connected in common to the group of elevators but it will of course be understood that 100 the several elevators may be operated independently.

What we claim as our invention is:—

1. In an elevator, a pair of vertically arranged rotatable members spaced apart and 105 rotating in unison, a plurality of pivots spaced adjacent to the peripheries of said members, carriers pivotally suspended from

said pivots between said rotatable members and a plurality of landing stages arranged at different levels and disposed transversely of the axis of said rotatable members and 5 leading directly to the periphery thereof.

2. In an elevator, a pair of discs spaced apart and rotatable about a horizontal axis, a series of passage ways arranged one above the other on each side of said discs and lead-

ing to the periphery thereof in a direction 10 transversely of their axis, carrier members suspended at their sides between said discs and being open at each end and adapted to swing into alignment with each of the passageways arranged on either side of said 15 discs.
